[57] **CLAIM**

The ornamental design for a storage rack for compact disks,
as shown and described.

DESCRIPTION

FIG. 1 is an isometric view of a storage rack for compact

disks showing my new design, the isometric view from the opposite side being a mirror image thereof;

FIG. 2 is an enlarged front elevational view thereof;

FIG. 3 is a top plan view of FIG. 2;

FIG. 4 is an end elevational view, the opposite end being a mirror image thereof;

FIG. 5 is an isometric view of an alternative embodiment of the storage rack for compact disks showing my new design, the isometric view from the opposite side being a mirror image thereof;

FIG. 6 is an enlarged front elevational view of FIG. 5;

FIG. 7 is a top plan view of FIG. 6;

FIG. 8 is an end elevational view of FIG. 6, the opposite end being a mirror image thereof;

FIG. 9 is an isometric view of a further alternative embodiment of a storage rack for compact disks showing my new design, the isometric view from the opposite side being a mirror image thereof;

FIG. 10 is an enlarged front elevational view of FIG. 9;

FIG. 11 is a top plan view of FIG. 10;

FIG. 12 is an isometric view of a further alternative embodiment of the storage rack for compact disks showing my new design, the isometric view from the opposite side being a mirror image thereof;

FIG. 13 is an enlarged front elevational view of FIG. 12;
and,

FIG. 14 is a top plan view of FIG. 13.
